CLAMP

Anthony M. Sasgen, Chicago, Ill.

Application January 15, 1943, Serial No. 472,443

2 Claims. (Cl. 144—305)

This invention relates to clamps and more particularly to work-holding clamps which may be used either as a fastening means, to clamp work to a supporting member, or as a vise, to clamp work directly between the jaws thereof.

For the most part, the clamps heretofore known are rather cumbersome and difficult to manipulate so that an operator, in placing and securing the clamp in position is oftentimes required to use both hands. In some cases, due to the nature of the work to be held or the conditions under which the work is being performed, it is often difficult, if not impossible, for a workman to have two hands free to manipulate the clamping device and, as a result, where the old clamping devices have been used, it has been difficult to effectively use such devices.

Therefore, it is an object of my invention to afford a clamp which may be easily manipulated with one hand to secure the work in position.

Another object of the invention is to afford a new and improved work-holding clamp which may be made largely from relatively inexpensive structural elements or parts such as metal stampings.

An additional object of the invention is to afford a work-holding clamp embodying a novel arrangement of levers for manipulating one of the clamping jaws into operative engagement with the work.

A further object of the invention is to afford a work-holding clamp embodying a novel arrangement of levers for manipulating one of the clamping jaws into operative engagement with the work and which clamp embodies novel means for adjusting said one of said jaws relative to the other clamping jaw embodied in the clamp.

Still another object of the invention is to afford, in one embodiment of the invention, a novel manually operable latching device for latching engagement with and control of the movement of an adjustable screw which supports one of the clamping jaws embodied in the device.

A further object of the invention is to afford, in one embodiment thereof, a novel combination supporting arm and guide sleeve for the adjustable clamping screw which supports one of the clamping jaws embodied in the device.

An additional object of the invention is to afford, in one embodiment thereof, a clamp embodying a pivoted clamping jaw having a novel, efficient and relatively large and effective bearing surface for engagement with the work.

Further objects of my invention are to afford a clamp wherein a strong grip may be had on

a piece of work by proper adjustment of a pivoted member and to afford a clamp wherein the grip thereof on a piece of work may be easily and quickly released.

5 Other and further objects of the present invention will be apparent from the following description and claims and are illustrated in the accompanying drawings which, by way of illustration, show preferred embodiments and the principles thereof and what I now consider to be the best modes in which I have contemplated applying these principles. Other embodiments of the invention embodying the same or equivalent principles may be used and structural changes may be made as desired by those skilled in the art without departing from the present invention and the purview of the appended claims.

In the drawings,

- 20 Fig. 1 is an elevational view showing a preferred form of the new clamp in position of use;
Fig. 2 is a view on line 2—2 in Fig. 1 partly in section and partly in top plan;
Fig. 3 is a view on line 3—3 in Fig. 1 partly in section and partly in plan;
25 Fig. 4 is a view of the form of the new clamp which is shown in Figs. 1, 2 and 3 but showing the same with one clamping jaw in released or ineffective position;
30 Fig. 5 is a fragmentary sectional view illustrating the various positions which the pivoted threaded latch member may assume relative to the adjustable screw which is embodied in the form of the new clamp which is shown in Figs. 1, 2, 3 and 4;
35 Fig. 6 is a sectional view on lines 6—6 in Fig. 5;
Fig. 7 is an elevational view similar to Fig. 1 but illustrating a modified form of the invention;
40 Fig. 8 is an edge elevational view of the form of the new clamping device which is shown in Fig. 7;
Fig. 9 is a view on line 9—9 in Fig. 7 partly in section and partly in top plan;
45 Fig. 10 is a view on line 10—10 in Fig. 7 partly in section and partly in top plan;
Fig. 11 is a detail view illustrating one use of the form of the new clamp which is illustrated in Figs. 7 to 11, inclusive;
50 Fig. 12 is a side elevational view illustrating another modification of the invention;
Fig. 13 is a top plan view of the modified form of the invention which is shown in Fig. 12 showing the parts of the clamp in effective or clamping position;

Fig. 14 is a view on line 14—14 in Fig. 12 partly in section and partly in plan;

Fig. 15 is a perspective view of a pivoted resilient clamping jaw, which is embodied in the form of the invention illustrated in Figs. 12 to 16, inclusive;

Fig. 16 is a view of the form of the new clamp which is shown in Figs. 12 to 16, inclusive, but showing the pivoted clamping jaw in released or ineffective position;

Fig. 17 is a detail view, partly in section, illustrating a modification of a part of the form of the new clamp which is illustrated in Figs. 12 to 16, inclusive; and

Fig. 18 is a view on line 18—18 in Fig. 17 partly in section and partly in top plan.

A preferred and typical embodiment of the new clamping device is illustrated in Figs. 1 to 6, inclusive, wherein it is generally indicated at 20, and is shown associated with and as used upon work 21 which may be of various characters and such, for example, as laminated strips of wood which may be clampingly held together by the new clamping device.

The form of the new clamping device 20 which is illustrated in Figs. 1 to 6, inclusive, comprises a clamping arm which includes a supporting frame 22. The supporting frame 22 is preferably formed of a pair of complementary relatively light structural elements in the form of metal stampings 23 and 24 secured together at selected spaced points by suitable fastening elements such as the rivets 25.

As best shown in Figs. 1 and 4 the supporting frame 22 of the clamp is shaped to afford an arm which extends approximately right-angularly from and relative to the body thereof, this arm being afforded by spaced extensions 35 and 36 of the frame 22 (Figs. 2 and 6).

As shown in Figs. 1 to 6, inclusive, the arm 35—36 of the supporting frame 22 of the new clamp is formed to afford, as an integral part thereof, a generally cylindrical guide sleeve 90 in which a metal bushing 99 is arranged. A clamping screw 40 is slidably projected through the metal bushing 99. The clamping screw 40 is provided, at one end, with a handle 91 and a clamping jaw 92 is swivelly or otherwise mounted upon the screw 40 at the opposite end thereof.

The form of the new clamping device which is illustrated in Figs. 1 to 6, inclusive, includes a second clamp arm 28 which is pivotally and adjustably mounted upon the supporting frame 22 of the clamp. As best shown in Fig. 3, the pivotal arm 28 is preferably formed from a pair of spaced and relatively light structural elements or members such as metal stampings or the like and which may be secured together in any suitable manner as, for example, in the manner which will be described presently.

It will be noted, in this connection, that the pivotal clamp arm 28 carries a clamping jaw 32 and that the clamping jaw 32 includes a portion which is arranged between and attached to the spaced structural elements 29—30 of the pivotal arm 28 by means of a suitable fastening element such as the rivet 31. This rivet 31 also serves to secure the spaced structural elements 29—30 of the pivoted clamp arm 28 together.

As shown in Figs. 1, 3 and 4, the clamping jaw 32 has a knurled gripping surface 33 and this knurled gripping surface 33 is provided with a transversely extending channel or recess 34, for a reason which will be described hereinafter.

As shown in Fig. 3 the spaced structural elements 29—30 of the pivoted clamp arm 28 are

provided with aligned openings 93. As also shown in Fig. 3, the openings 93 are adapted to be registered with the openings 26 in the supporting frame 22, this being accomplished by inserting the body of the relatively narrower supporting frame 22 between the parts 29—30 of the pivoted clamp arm 28 to effect registry of a selected one of the openings 26 with a selected pair of the openings 93. The pivotal connection between the clamp arm 28 and the supporting frame 22 of the other clamp arm 22—23—24—34—35—36 may then be effected by inserting the pin 27 through the selected and aligned openings 26—93.

The pivoted clamp arm 28 includes a manual operable operating lever 46 which is also preferably formed from a pair of relatively light structural elements such as the metal stampings 94 and 95 which may be secured together by any suitable fastening elements such as the rivets 96.

The operating lever 46 is pivotally mounted upon the body of the clamp arm 28, as at 47, and includes a nose or cam portion 97 which is adapted to have camming engagement with the body of the supporting frame 22, as shown in Fig. 4.

A threaded latch member 38 is arranged between the spaced arms 35 and 36 of the supporting frame 22 of the clamp arm 22 and is pivoted therebetween and thereto, as at 37. This latch member 38 has one surface thereof which is threaded, as at 39, for threaded engagement with the clamping screw 40. The pivoted latch member 38 is provided with a notched or serrated edge portion 45 for a reason which will be explained hereinafter.

As best shown in Figs. 5 and 6, the threaded portion 39 of the pivoted latch member 38 projects into and works in a cut-out portion or opening 98 which is provided in a generally cylindrical bushing 99 which is arranged in the guide sleeve 90. The bushing 99 may be secured in the guide sleeve 90 in any suitable manner, as by frictional engagement and, as shown, the screw 40 projects through and is guided in the bushing 99.

A coil spring 42 has one end portion thereof anchored, as at 43, between the arms 35 and 36 of the supporting frame 22 of the clamp arm 22—23—24—35—36 and the other end portion of this spring 42 is attached, as at 44, to the pivoted and threaded latch member 38.

The use and operation of the form of the new clamp illustrated in Figs. 1 to 6, inclusive, of the drawings are as follows: The clamp arm 28 may be disposed in a selected adjusted position relative to the supporting frame 22 and the other clamp arm 22—23—24—35—36 by inserting the supporting frame 22 between the structural elements or parts 29 and 30 of the clamp arm 28 with the openings 93 in the parts 29 and 30 in registry with a selected one of the openings 26 in the supporting frame 22, whereupon the pivot pin 27 may then be inserted through the thus registered openings 93 and 26. In this manner the clamp arm 28 may be initially positioned upon and relative to the supporting frame 22 for use with work 21 of a particular size, thickness, shape, etc.

The swivelled clamping jaw 92 may then be moved into engagement with the work 21 as follows: This is accomplished by the operator or user of the new clamp pressing his thumb against the serrated or notched edge portion 45 of the pivoted and threaded latch member 38 so as to pivot this member 38, against the action of its resetting spring 42, from its normal or effective and latching position, as in Fig. 1 and as in full lines in Fig. 5, into unlatched position in which

the member 38 is shown in dotted lines in Fig. 5. This moves the threaded portion 39 of the latch member 38 out of engagement with the threads of the clamping screw 40. The clamping screw 40 may then be slid downwardly, in the guide sleeve 90 and bushing 99, by pressing upon the handle 91, thus moving the swivelled clamping jaw 92 into engagement with one face of the work 21.

The clamping jaw 32-33 may then be clampingly engaged with the work 21, opposite the swivelled clamping jaw 92, by manipulating the hand lever 46, downwardly, as seen in Fig. 4.

This motion of the hand lever 46 pivots the same about the pivot 47 and cams the nose or cam portion 97 thereof against one edge of the supporting frame 22 of the other clamp arm 22-23-24-35-36. This camming action pivots the clamp arm 28 about the pivot 27 and thus moves the clamping jaw 32-33 carried thereby into clamping engagement with the work 21.

In the event that it is desired to release the swivelled clamping jaw 92 from clamping engagement with the work 21, without changing the position or adjustment of the clamp arm 28 relative to and upon the supporting frame 22 of the other clamp arm 22-23-24-35-36, this may readily be accomplished by manually pivoting the threaded latch member 38, against the action of its resetting spring 42 from effective to ineffective position, from full to dotted line position, as seen in Fig. 5, thereby moving the threaded portion 39 of the pivoted latch member 38 out of threaded engagement with the clamping screw 40. While manually holding the pivoted and threaded latch member 38 in ineffective position (as in dotted lines in Fig. 5) the clamping screw 40 may be raised by means of its handle 91 so as to move the swivelled clamping jaw 92 carried thereby out of clamping engagement with the work 21 without changing the position or adjustment of the clamp arm 28 relative to and upon the supporting frame 22 of the other clamp arm 22-23-24-35-36. This is particularly useful and desirable in instances where it may be desired to move the new clamp from one position to another upon the work 21 or to move the new clamp from one work piece 21 to another work piece of the same size or thickness, etc.

The knurled surface 33 of the clamping jaw 32 is adapted to engage the work 21 at one side thereof and facilitates the gripping action of the clamping jaw 32.

In certain instances it may be desirable to hold or clamp a round or cylindrical object between the clamping jaws 92 and 32 and this is facilitated by the provision of the channeled recess 34 in the gripping surface 33 of the clamping jaw 32, this channeled recess 34 being adapted to receive a portion of a round or cylindrical object which is clampingly held between the two clamping jaws 92 and 32.

A modified form of the invention is illustrated in Figs. 7 to 11, inclusive, and comprises a pair of clamp arms 48 and 60 which are, in general, similar in form and construction to the clamp arms 22-23-24-35-36 and 28, respectively, in the form of the invention which is illustrated in Figs. 1 to 6, inclusive.

It will be noted, in this connection, that the clamp arm 48, like the clamp arm 22, is preferably made of a pair of relatively light structural elements in the form of metal stampings 52 and 53, joined together by suitable fastening elements, such as rivets 51, and that the clamp arm 60 is

likewise preferably made of a pair of relatively light structural elements in the form of metal stampings 52 and 53.

As shown in Fig. 10, the structural elements or metal stampings 52 and 53 are, in this form of the invention, integrally joined, as by welding or the like, and are so formed or shaped as to provide a substantially cylindrical guide sleeve 54. This guide sleeve 54 is internally threaded for the reception of a threaded clamping screw 55 which works therethrough.

The clamping screw 55 is provided at one end with a clamping jaw 100, which may be swivelly or otherwise mounted thereon, and at its other end the clamping screw 55 is provided with a knurled hand knob 57. Threaded upon the clamping screw 55, between the guide sleeve 54 and the hand knob 57, is a clamping nut 56.

As shown in Fig. 9, the clamp arm 60 carries a clamping jaw 63, which has a knurled gripping surface 65, and this clamping jaw 63 is rotatably mounted upon and between the structural elements 49 and 50 of the clamp arms 60 by means of a pivot pin 64 which also serves to secure the arms 49 and 50 together and in spaced relationship.

As shown in Figs. 7 and 11, the clamping jaw 63 is provided with a channeled recess 66, in the face thereof which is opposite the knurled face 65, and the channeled surface 66 and the knurled gripping surface 65 on the gripping jaw 63 are selectively or alternately usable, as will be explained more fully hereinafter.

The clamp arm 60, unlike the clamp arm 28 of the form of the invention shown in Figs. 1 to 6, inclusive, is not adjustable relative to the clamp arm 48 by reason of the fact that the clamp arm 60 is pivotally mounted upon the clamp arm 48 by means of a pivot pin 59 which permanently secures the two clamp arms 48 and 60 together, with the structural elements 52 and 53 of the clamp arm 48 disposed between the structural elements 49 and 50 of the clamp arms 60, as shown in Fig. 9.

Pivotedly mounted upon the clamp arm 60, as at 62, is a hand lever 61. This hand lever 61 has a nose or cam portion 101, which is similar to the cam portion 97 of the lever 46.

As shown in Figs. 8 and 9, the lever 61 is also formed from a pair of relatively light structural elements 102 and 103 which are joined together by suitable fastening elements such as the rivets 104.

In the use of the form of the invention which is illustrated in Figs. 7 to 11, inclusive, the clamping screw 55 may be adjusted to bring the clamping jaw 100 carried thereby into engagement with one side or face of the work 67. This is accomplished by manipulating the hand knob 57, and when this adjustment is completed the clamping screw 55 and the clamping jaw 100 carried thereby may be secured in the adjusted position by manipulating the clamping nut 56 on the clamping screw 55 into engagement with the guide sleeve 54.

If the work is a flat-sided object, such as the work 67, the clamping jaw 63 may be rotated upon its pivot or mounting 64 so as to position or dispose the knurled surface 65 thereof for engagement with a flat surface of the work 67, opposite the clamping jaw 100, whereupon the thus positioned clamping jaw 63 may be moved into clamping engagement with the work 67 by rocking the lever 61 about its pivot 62 into the position in which the parts are shown in Fig. 7.

This movement of the lever 61 moves the nose or cam portion 101 thereof into camming engagement with the body or supporting frame of the clamp arm 48 and thereby rocks the clamp arm 60, about its pivot 59, upon and relative to the clamp arm 48, thus moving the clamping jaw 65, which is carried by the clamp arm 60, into clamping engagement with the work 67.

However, in certain instances it may be desirable to clamp a round or cylindrical object between the clamping jaws 63 and 100. In such instances the clamping jaw 63 may be rotated upon its mounting 64 so as to bring the channeled or recessed surface 66 thereof into a position opposite or in clamping relationship with the clamping jaw 100. A round or cylindrical object, such as 68, may then be disposed upon the channeled surface 67 of the clamping jaw 63 and the clamping jaw 63 moved into clamping engagement by manipulation of the hand lever 61, in the manner hereinbefore described.

Another modification of the invention is shown in Figs. 12 to 16, inclusive, and in this form of the invention the two clamp-supporting arms 74 and 79 are formed as integral parts of the frame or body 69 of the clamp which, in turn, is preferably formed of a pair of relatively light structural elements 70 and 71, such as metal stampings or the like, which are fastened together by suitable fastening elements such as the rivets 72.

In this form of the invention the two clamp-supporting arms 74 and 79 extend substantially or in general parallel to each other and the structural parts or elements 70 and 71 of the clamp-supporting arms 74 are integrally joined and shaped to provide a substantially cylindrical guide sleeve 75, which is similar to the guide sleeve 54.

The guide sleeve 75, like the guide sleeve 54, is internally threaded and a clamping screw 76 is threaded therethrough. This clamping screw 76 is provided at one end with a knurled hand knob 78 and at its other end the clamping screw 76 carries a clamping jaw 104 which may be swivelly or otherwise mounted upon the clamp-screw 76.

A knurled clamping nut 77 is threaded onto the clamp-screw 76 between the guide sleeve 75 and the knurled hand knob 78.

A hand lever 80 is pivotally mounted upon the clamp-supporting arm 75, as at 81, and between the structural elements or parts 70 and 71 of the clamp-supporting arm 79. The lever 80 has a cam or nose portion 82 and this cam or nose portion 82 of the hand lever 80 is engageable with one surface of a resilient clamping member 85 which is preferably formed of a piece of resilient flat metal spring stock slightly curved, as shown in Figs. 12, 15 and 16. The resilient clamping member 85 is provided at one end with a pair of laterally extending ears 84 and these ears 84 project into openings 83 which are provided in the structural elements 70 and 71 of the clamp, and are inserted therein prior to the time the structural elements 70 and 71 are riveted or otherwise fastened together, as at 72. In this manner the resilient clamping member 85 is pivotally mounted upon and relative to the clamp-supporting arm.

As shown in Figs. 12, 13 and 16, the body of the clamp 69 is provided with a handle or thumb rest portion 73 which is formed as an integral extension of the structural elements 70 and 71 which are, as shown in Fig. 13, preferably bent outwardly relative to each other so as to afford

a relatively wide thumb rest when using this form of the new clamp, as will be explained presently.

The use and operation of the form of the new clamp shown in Figs. 12 to 16, inclusive, of the drawings, are as follows: The clamping jaw 104 may be positioned in engagement with one side of the work 86 by manipulating the hand knob 78 of the clamping screw 76, whereupon the clamping nut 77 may be adjusted into engagement with the guide sleeve 75. The hand lever 80 may then be pivoted from its normal or ineffective position, as in Fig. 16, into effective or clamping position as in Fig. 12. This may be accomplished by placing the thumb upon the thumb rest portion 73 and grasping the hand lever 80 with the same hand.

When the hand lever 80 is thus moved from its normal or ineffective position, as in Fig. 16, into effective or clamping position as in Fig. 12, the nose or cam portion 82 thereof bears or cams against one surface of the resilient clamping member 85 and urges the latter into clamping engagement with the work 86 at the side thereof which is opposite the clamping jaw 104.

It will be noted, in this connection, that when the resilient clamping member 85 is in effective or clamping position it provides a relatively large bearing or clamping surface which is more effective than the relatively small clamping surface of the nose or cam portion 82 of the lever 80 would be if it engaged directly with the work inasmuch as there would be a tendency for such a relatively small cam surface as might be afforded by the nose or cam portion 82 of the lever 80 to slip relative to the work or to permit the work to slip relative thereto.

In order to release the parts of the form of the new clamp shown in Figs. 12 to 16, inclusive, it is merely necessary to manipulate the clamping lever 80 from effective or clamping position in which it is shown in Fig. 12 into ineffective position in which it is shown in Fig. 16, without changing the adjustment of the clamp-screw 76 and its clamping jaw 104 upon or relative to the clamp-supporting arm 74.

A modified construction of one part of the form of the invention which is shown in Figs. 12 to 16, inclusive, is illustrated in Figs. 17 and 18. This modification is substantially similar to the form of the invention which is illustrated in Figs. 12 to 16, inclusive, and parts thereof which correspond to parts in the form of the invention which are shown in Figs. 12 to 16, inclusive, have been given the same reference numerals followed by the additional reference character *a*.

In the form of the invention which is shown in Figs. 17 and 18, internal threads are omitted from the guide sleeve for the clamp-screw and the guide sleeve 75a is made somewhat larger, in diameter, than the guide sleeve 75 for the reception of an internally threaded flanged metallic bushing 87. This bushing 87 is inserted into the guide sleeve 75a and may be secured to the guide sleeve 75a in any suitable manner as by peening one flange portion 88 thereof into a resultant indented portion of the guide sleeve 75a, as shown at 87 in Fig. 17. Except as thus described, however, the modification which is illustrated in Figs. 17 and 18 is substantially similar in construction, use and operation to the form of the invention which is illustrated in Figs. 12 to 16, inclusive, and hence need not be described in further detail.

It will be noted that in all of the several forms

thereof which are illustrated in the drawings the pivoted clamp arm and the clamping jaw carried or controlled thereby, may be manipulated into and out of effective or clamping position relative to and without disturbing the position or adjustment of the other clamp arm and the clamping screw and clamping jaw carried thereby. This enables the operator or user of the new clamp to manipulate the same and to shift the clamp upon or relative to the work with and by the use of only one hand, leaving the other hand free for necessary work.

It will thus be seen from the foregoing description, considered in conjunction with the accompanying drawings, that the present invention provides a new and improved clamping device and accomplishes its intended objects and has the desirable advantages and characteristics including those hereinbefore pointed out and others which are inherent in the invention.

While I have illustrated and described selected embodiments of my invention, it is to be understood that these are capable of variation and modification and I therefore do not wish to be limited to the precise details set forth but desire to avail myself of such changes and alterations as fall within the purview of the following claims.

I claim:

1. A clamp comprising a pair of cooperating jaw-supporting arms, one of which arms is substantially L-shaped and each formed of separate and relatively light and flat structural elements, a clamping jaw carried by each of said jaw-supporting arms, the other of said jaw-supporting arms being pivotally mounted substantially midway between its ends upon the substantially L-shaped jaw-supporting arm, means for pivotally mounting said other jaw-supporting arm at different times in various positions upon and relative to said one jaw-supporting arm, the structural elements forming said pivotally mounted jaw-supporting arm including portions spaced from each other, a portion of said substantially L-shaped jaw-supporting arm being disposed be-

tween the spaced portions of said pivotally mounted jaw-supporting arm, said means for pivotally mounting said other jaw-supporting arm in various positions including a plurality of spaced apertures formed in said substantially L-shaped jaw-supporting arm and a pair of aligned apertures formed in the said spaced structural elements of said pivotally mounted jaw-supporting arm and selectively registerable with the said apertures formed in said substantially L-shaped jaw-supporting arm, said means for pivotally mounting said pivotally mounted jaw-supporting arm including a pivot pin selectively insertible into said aligned apertures, and means for manipulating each of said clamping jaws toward and from and relative to each other and into and out of clamping engagement with an object disposed therebetween.

2. A clamp comprising cooperating substantially L-shaped jaw-supporting arms, clamping means carried by each jaw-supporting arm at opposed ends thereof and the other ends thereof being free, the said arms being adjustably pivotally connected together substantially medially of their respective ends and such pivotal connection effecting an overlapping relationship of the arms intermediate their free ends, a movable lever having a camming surface for engagement with one of the arms and to effect movement of the other arm, said lever being pivotally connected to the free end of one of the arms and overlapping a portion thereof when clamping work and having a portion in non-overlapping relationship with said last mentioned arm which permits ready manipulation of the said lever to either clamp or unclamp work, the said adjustable pivotal connection of the two jaw-supporting arms consisting of a plurality of spaced apertures formed in one of the arms and an aperture formed in the other arm, the said apertures in each arm being selectively registerable with each other, and a pivot pin selectively insertible into the registered apertures.

ANTHONY M. SASGEN.
